PORTABLE ELECTRIC FOOD MIXER

Edward W. Peterson, Deerfield, Ill., assignor to Rival Manufacturing Company, a corporation of Missouri

Filed Aug. 4, 1967, Ser. No. 8,122

Term of patent 14 years

(Cl. D44—1)

FIG. 1 is a top plan view of a portable electric food mixer showing my new design;

FIG. 2 is an elevational view from the bottom of FIG. 1;

FIG. 3 is a bottom plan view;

FIG. 4 is an elevational view from the left of FIG. 1; and

FIG. 5 is an elevational view from the right of FIG. 1. The dominant features of my design reside in the portions shown in solid lines.

I claim:

The ornamental design for a portable electric food mixer, as shown and described.
